CLEANING OIL WELL DRILLING FLUIDS

Roy Cross and Matthew Forbes Cross,
Kansas City, Mo.

Application March 6, 1937, Serial No. 129,449

4 Claims. (Cl. 210—62)

This invention relates to the art of earth boring and more particularly to a method of cleaning oil well drilling fluids. The application is a continuation-in-part of our copending application 5 Serial No. 112,761, filed November 25, 1936.

As is well known in the art, a fluid is pumped downwardly through the drill stem of a rotary drilling rig, passes through holes in the bit, washes over the cutting faces of the bit, and rises 10 to the surface through the annular space surrounding the drill stem, this annular space approximating the amount by which the diameter of the bit exceeds the diameter of the drill stem. The principal functions of the drilling 15 fluid in this use are to seal the walls of the open hole, to lubricate the bit, to carry the cuttings from the bit to a point outside the hole, to prevent the settling of cuttings and the consequent seizure of the bit, and to supply a static 20 head sufficient to overcome pressures encountered during boring which would blow the fluid from the bore.

In the present art there are a number of difficulties in accomplishing all these functions. 25 Many of these have been pointed out in our copending application Serial No. 112,761. A difficulty which causes great expense due to wear of the equipment is that of being unable to separate fine abrasive material from the drilling fluid. 30 This abrasive material ordinarily is in the form of fine sand. This causes excessive wear of the drill stem, the drill bit and of pumps. In average drilling the sand content may vary greatly. A sand content of 1½ to 3% by weight of mud is 35 the maximum desirable amount. It is seldom that a concentration as low as this can be obtained.

Having the foregoing in mind, an object of this 40 invention is to provide a novel method of cleaning the drilling fluid of abrasive material.

One form of treatment of oil well drilling fluid in accordance with the practice of our invention is shown in the accompanying drawing. A is the suction pit; B, the mud pump; C, the flexible 45 hose connecting pump B with the drill stem; D is the drill stem; E is the drill bit; F is the bore made; G is the surface casing; H is a vibrating screen; J, a settling pit; K is a filter; L is a centrifuge; M is a refuse pit; N is a swivel connecting C with D; and P is the rotary table of drilling rig O. A description of the operation of the 50 illustrated apparatus follows: Drilling mud is picked up from suction pit A by pump B and is forced through the line and flexible hose C through swivel N and downwardly through drill

stem D. The mud passes through holes in the bit E and proceeds upwardly through the hole F, surface casing G, and proceeds from the outlet of G to the vibrating screen H. The screen H removes considerable amounts of shale and 5 larger particles. The mud proceeds from H to settling pit J. In this pit there is further dropping or separation of cuttings by gravity. From J the mud may be pumped through the centrifuge L, which contains the customary pumping means. 10 During this period the valve between L and K is closed and the valve between L and A is opened. The centrifuge separates the abrasive material from the mud and ejects the cleaned mud through the line from L to A; and ejects the waste abrasive 15 material through the line to refuse pit M simultaneously. This type of operation is more successful with a brine drilling fluid, due to the fact that there is no gelling action by the natural mud drilled in a brine solution. Thus, the foreign matter separates quickly and much more easily than is possible with a fresh water mud. 20 With this type of operation the refuse may be pumped from the refuse pit M to the filter K in which further separation of mud and abrasive is 25 effected, the mud fluid being ejected from K into the suction pit A. This reclaims all of the clear weighted drilling fluid where a soluble weighting material has been used. The mud is almost completely cleaned of abrasive material and refuse. 30 If it is desired to completely clean all the mud of undesirable material, the valve between L and A may be closed and the valve between L and K may be opened. With this setting the lighter cleaned mud passes from the centrifuge through 35 the filter K and thence to suction pit A. This completely cleans the mud.

A modification of the practice of this invention is as follows: The mud is pumped from settling pit J to filter K, which contains pumping 40 means. The valve between K and L is closed, and the valve between L and A is closed, and the valve between line J—K and refuse pit M is closed. The valve between J and K is opened. The mud is filtered by K and completely cleaned. 45 It is then ejected to suction pit A. In J is located a jet by means of which refuse is removed from J and taken to refuse pit M. It will be apparent that all material in M can be cleaned by filtering through filter K.

To those familiar with the art it is not ordinarily thought feasible to filter the drilling fluid whether it be fresh water or brine in character. This is because of the fact that even where no weight is used, the fluid as observed contains a 55

large amount of solid matter. The only way in which the mud is cleaned is by dilution and by the action of the settling pit, and often by the vibrating screen. However, if a mud is continually cleaned as drilling progresses the total amount of solid material that must be removed is comparatively small. For example, a ten-inch hole being drilled at a rate of 100 feet per day gives only 275 pounds of solid material per hour. A filter for removing this amount of material at this rate is a requirement easily met. The filter used may be of the Sweetland type or may be a rotary type. With a rotary type filter, a screen having openings smaller than the particle size of the sand which is to be removed may be used as the filter, in combination with a cleaning knife which removes the cake at each revolution of the screen.

Several ways of operating this invention have been disclosed, but these disclosures are not intended as limitations on the use of any combination of equipment specifically described. For example, there may be a varying number of pits, there may or may not be a vibrating screen, a filter may be used alone with fresh water or brine mud, the centrifuge may be used alone, or the centrifuge and filter may be used in combination with each other.

The advantages in the use of this method of cleaning mud are that maintenance of drilling and pumping equipment is greatly decreased, and that where soluble weighting materials are used the weighted solution may be recovered completely.

Having thus described the invention, what we claim as new and desire to secure by Letters Patent of the United States is:

1. In combination with a rotary drilling apparatus for oil and gas wells, an exit conduit from the drill hole to a screen for removing large solid particles, a settling pit, a conduit between said screen and said settling pit, a centrifuge for removing smaller solid particles not removable by the screen, a conduit between said settling pit and said centrifuge, a filter adapted to remove substantially all of the liquid from the solid materials, a conduit between said filter and the settling pit, a conduit between said filter and the centrifuge, a suction pit, a conduit between said suction pit and said filter, another conduit between said suction pit and said centrifuge, and a conduit including pumping means between said suction

pit and the drilling apparatus for recycling the cleaned drilling fluid.

2. In the art of drilling oil and gas wells, the method of treating a mud-laden drilling fluid containing a weighting agent as it comes from a drilling hole which comprises the steps of passing the same through a screen to remove shale and large particles, sending the screen-passed fluid to a settling tank, settling the fluid therein to permit cuttings to separate by gravity, removing the separated cuttings to a refuse pit, sending the remaining fluid from the settling tank to a centrifuge, centrifuging the drilling fluid therein to separate sand-like abrasive material, removing said separated abrasive material from the centrifuge to the refuse pit, passing the cleaned mud from the centrifuge to a suction pit, sending the mixed cuttings and abrasive material from the refuse pit to a filter and filtering the same, and passing the filtrate from said filter to the suction pit to join the cleaned mud from the centrifuge, and reusing the cleaned fluid mixture in the drilling system.

3. In the art of drilling oil and gas wells, the method of treating a mud-laden drilling fluid containing a weighting agent to remove undesirable solids and abrasive materials accumulated in a drilling hole and to recondition the same which comprises the steps of centrifuging the fluid, passing the cleaned centrifuged mud to a receptacle, filtering the separated abrasive material from the centrifuge by a filter and combining the filtrate from the filter with the cleaned mud in the receptacle, and recirculating the mixture to the drilling hole.

4. In the art of drilling oil and gas wells, the method of treating and reconditioning a mud-laden drilling fluid containing a weighting agent as it comes from a drilling hole which comprises the steps of separating undesirable large solids and cuttings, centrifuging the remaining mud-laden drilling fluid, filtering the cleaned mud coming from the centrifuge, mixing the aforesaid large particles and cuttings with the separated abrasive material from the centrifuge, filtering the cuttings and abrasive mixture and combining the filtrate therefrom with the filtered mud originally cleaned by the centrifuge, and recirculating the mixture for reuse.
